INVENTOR.

Sanford J. Blackwell,

BY

Geo. P. Kimmel.

ATTORNEY.

UNITED STATES PATENT OFFICE

SANFORD J. BLACKWELL, OF ATLANTA, GEORGIA, ASSIGNOR OF ONE-FOURTH TO HENRY WOODFIN McLARTY, OF ATLANTA, GEORGIA, ONE-FIFTH TO COBB BENNING, OF ATLANTA, GEORGIA, AND ELEVEN-TWENTIETHS TO RANSOM AND COMPANY, INC., OF ATLANTA, GEORGIA

BOTTLE

Application filed March 7, 1929. Serial No. 344,949.

This invention relates to a bottle, more particularly to a bottle adapted to contain milk, cream, or the like, and has for its primary object to provide, in a manner as hereinafter set forth, a bottle of such class which is so constructed that it may be effectively closed by the usual type of pasteboard closure cap with the latter disposed in a manner to provide for the drainage therefrom of rain, snow, or the like, to which milk bottles in their ordinary use are commonly subjected, thereby reducing to a minimum the likelihood of the cap becoming softened by its exposure to weather conditions.

15 A further object of the invention is to provide a bottle as aforesaid wherein ready access may be had to an edge portion of the closure cap therefor to remove the latter, thereby eliminating the necessity of either 20 using an instrument to remove the cap, or of forming the cap with a removal tab.

With the foregoing and other objects in view, the invention consists of the novel construction, combination and arrangement of 25 parts as hereinafter more particularly described, and as illustrated in the accompanying drawings wherein is shown an embodiment of the invention, but it is to be understood that such drawings and description are to be 30 taken as illustrative and that the invention is intended to be limited only by the scope of the claims hereunto appended.

In the accompanying drawings in which like numerals are employed to designate like 35 parts throughout the same:

Figure 1 is a fragmentary, longitudinal section of a bottle constructed in accordance with this invention.

Figure 2 is a top plan thereof.

40 Figure 3 is a fragmentary elevation thereof.

Referring to the drawings in detail, the numeral 1 designates a bottle of the milk bottle type formed at its open end in the usual manner with a bead 2. Formed in the upper edge of the side wall of the bottle is a notch 3 the side walls of which converge in a downward direction and the bottom wall of which is flush with the upper face of a circumferentially 45 extending shoulder 4 formed interiorly of

the bottle. The shoulder 4 extends at a slight upward inclination from both sides of the notch 3 with the highest point of the shoulder 4, which is indicated at 5, disposed diametrically opposite to the notch 3. 55

Formed in the outer face of the side wall of the bottle is a concavity 6, the side marginal portions of which extend beyond the side walls of the notch 3. The concavity 6 extends through the upper edge of the bottle 60 and is disposed slightly inwardly of the vertical plane of the outer periphery of the shoulder 4. The wall of the concavity extends at a slight downward and outward inclination and terminates at its lower extremity a substantial distance below the bottom 65 wall of the notch 3.

The bottle is adapted to be closed by a circular cap 7 which is wedged through the open end of the bottle into seated position on the shoulder 4. With the cap 7 in position, one edge portion thereof is extended slightly into the concavity 6 and due to the inclination of the shoulder 4, the cap 7 slopes gradually toward the notch 3 whereby any moisture which 75 may be deposited on the cap, as by rain or melting snow, will be drained from the cap through the notch 3, thereby removing the likelihood of such moisture soaking into the cap to damage the same. 80

When it is desired to remove the cap, it is merely necessary to move a thumb or finger upwardly along the wall of the concavity 6 whereby the exposed edge portion of the cap will be engaged by the thumb or finger to remove the cap from its seat. 85

It is thought that the many advantages of a bottle in accordance with this invention will be readily apparent, and although the preferred embodiment is as illustrated and described, yet it is to be understood that various changes in the size, shape and arrangement of parts may be made, so long as such changes fall within the scope of the invention as defined in the appended claims. 95

What I claim is:

1. A bottle having its side wall formed with a circumferentially extending interior shoulder and further formed in its upper edge with a notch having its bottom wall flush 100

with the upper face of the shoulder, said shoulder extending at an upward inclination from both sides of said notch and having its uppermost portion disposed diametrically opposite to said notch.

5 2. A bottle having its side wall formed with a circumferentially extending interior shoulder and further formed in its upper edge with a notch having its bottom wall flush with the upper face of the shoulder, said side wall being further formed in its outer face with a concavity having its side marginal portion extending beyond the side walls of the notch, said shoulder extending 10 at an upward inclination from both sides of said notch and having its uppermost portion disposed diametrically opposite to said notch.

15 3. A bottle having its side wall formed with a circumferentially extending interior shoulder and further formed in its upper edge with a notch having its bottom wall flush with the upper face of the shoulder, said side wall being further formed in its 20 outer face with a concavity having its side marginal portion extending beyond the side walls of the notch, the wall of the concavity extending across the vertical plane of the outer peripheral portion of the shoulder at a 25 downward and outward inclination, said shoulder extending at an upward inclination from both sides of said notch and having its uppermost portion disposed diametrically opposite to said notch.

30 35 In testimony whereof, I affix my signature hereto.

SANFORD J. BLACKWELL.
